UNITED STATES PATENT OFFICE

168,904

PAPER CUTTER CASE

Richard C. O'Brien, Dayton, and Viktor Schreckengost, Cleveland, Ohio, assignors to Harris-Seybold Company, Cleveland, Ohio, a corporation of Delaware

Application May 5, 1951, Serial No. 15,075

Term of patent 14 years

(Cl. D58—12)

To all whom it may concern:

Be it known that we, Richard C. O'Brien and Viktor Schreckengost, citizens of the United States, residing respectively at Dayton, county of Montgomery, and State of Ohio, and Cleveland, county of Cuyahoga, and State of Ohio, have invented a new, original, and ornamental Design for a Paper Cutter Case, of which the following is a specification, reference being had to the accompanying drawings, forming a part thereof, in which

Fig. 1 is a perspective view of a paper cutter case, showing my new design, the opposite side and end being substantially the same as those shown.

Fig. 2 is a side elevational view of the case in disassembled form, with the base portion supported upon the top of the cover portion thereof.

Fig. 3 is a perspective view of the base portion only of the case, and

Fig. 4 is an end elevation of the case in disassembled form with the base portion supported on the cover portion thereof.

We claim:

The ornamental design for a paper cutter case, substantially as shown and described.

RICHARD C. O'BRIEN.
VIKTOR SCHRECKENGOST.
